[57] CLAIM

The ornamental design for a removable combined hard disk drive holder and cassette, as shown and described.

DESCRIPTION

FIG. 1 is a front, right, top perspective view of a combined removable hard disk drive holder and cassette showing my new design;

FIG. 2 is a front, right, top perspective view thereof, the removable hard disk drive holder is shown separately for clarity of illustration;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top view thereof;

FIG. 8 is a bottom view thereof;

FIG. 9 is a front, right, top perspective view thereof, the cassette is shown separately for clarity of illustration;

FIG. 10 is a right side elevation view thereof;

FIG. 11 is a left side elevation view thereof;

FIG. 12 is a front elevation view thereof;

FIG. 13 is a rear elevation view thereof;

FIG. 14 is a top view thereof; and,

FIG. 15 is a bottom view thereof.
